CLAMP

August B. Wolbers, 6390 Monitor St., Pittsburgh 17, Pa.
Filed Jan. 11, 1962, Ser. No. 165,533
7 Claims. (Cl. 248—41)

This invention relates broadly to clamps, and more particularly, to clamps for use with hospital beds.

To intravenously feed a patient in a hospital bed, it is necessary to support the feeding bottle from an elevated position above the patient. Generally such bottles are hung from the top of a pole known generally as an I.V. or intravenous pole. Many hospital beds provide receptacles for such poles secured to the bedframe at one or more locations on the bedframe. The aforementioned receptacles are immovable and very often the doctor or nurse will discover that the clamp is not located in a position on the bedframe that is convenient for intravenous feeding. Often the tube from the feeding bottle must be twisted and turned in several directions to place the needle to be inserted in a vein of the patient into the proper position. This may not only cause discomfort to the patient because of the strain of the tube on the needle but also may even create a stoppage in the feeding tube from crimping thereof. Many hospitals alleviate this problem by using intravenous poles mounted on floor dollies whereby the feeding bottle may be positioned at any convenient location about the bed. However, this too has serious disadvantages in that floor dollies are comparatively expensive and take up a great deal of storage space and thus not too many of them can be practically available for use and further they take up considerable space at the bedside and are understandably in the way when moving about or working with the patient. Furthermore, while in use, they may be bumped into and moved or even knocked over with obvious dire consequences.

I have invented a clamping device for use with any standard hospital bed which may be positioned at practically any location on the frame of the bed which when used with an intravenous pole will securely lock the pole and the clamp in position on the frame and which is immovable when locked and yet when unlocked may be moved along the bedframe in adjustment to whatever position is desired. Likewise pole elevation is adjustable as desired through the same locking means.

I provide a clamp for use with hospital beds and the like in combination with a pole member such as an intravenous pole and the like comprising a face member adapted to engage an inner portion of a bedframe, said face member having arm means adapted to extend below and across the lower portion of a bedframe, a back member being pivotally supported on said arm means whereby a portion of said bedframe is disposed between said face and back members, said face member having flange means adapted to engage a top portion of said bedframe, said face member having a plurality of flanges disposed in spaced relation one above the other with corresponding openings therein, said pole member extending through said openings, said back member having a lower portion extending below said pivotal support and a locking member mounted on said face member swingable to simultaneously engage said lower portion of the back member and said pole member whereby said back member is pivoted into engagement with said inner portion of a bedframe and said pole member is bound in said openings.

Preferably, to facilitate the mounting of my clamp on a bedframe, said face member is comprised of upper and lower elements hingedly joined and swingable with respect to each other and having spring means to resiliently urge said elements into coplanar relationship.

So that my clamp is adaptable to variations in thick-

2

ness of bedframes and is thus more universal, I further preferably provide a locking means that is yieldable both in vertical and horizontal directions.

It will be obvious to those skilled in the art that my clamp can be used with many other pole devices such as bed guards, dinner or writing trays and so forth and I do not intend to limit my invention to intravenous poles but have simply described my device in combination with intravenous poles as a matter of convenience in illustration.

Other details, objects and advantages of the invention will become apparent as the following description of certain present preferred embodiments thereof proceeds.

In the accompanying drawings, I have shown certain present preferred embodiments of the invention in which

FIGURE 1 is an orthogonal perspective view of one embodiment of my clamp in combination with a pole member and mounted on a bedframe;

FIGURE 2 is a transverse cross-sectional view of the embodiment shown in FIGURE 1;

FIGURE 3 is an orthogonal perspective view of another preferred embodiment of my clamp in combination with a pole member and mounted on a bedframe;

FIGURE 4 is a transverse cross-sectional view of the embodiment shown in FIGURE 3; and

FIGURE 5 is an orthogonal perspective view of the lower face element of the embodiment shown in FIGURE 3.

Referring to the drawings, and initially to FIGURE 1, I have illustrated my clamp, designated generally as clamp 10, disposed on a bedframe 11 with an intravenous pole 12 secured therein. Clamp 10 comprises a face member 13 and a back member 14. Face member 13 has a pair of projecting arms 15 which are curled at their ends to form hinge eyes 16. As shown in FIGURES 1 and 2, back member 14 is pivotally supported on flange arms 15 by hinge pin 17, the ends of which are disposed in hinge eyes 16. Face member 13 has flange portions 18 adapted to engage the top portion 19 of bedframe 11. As is readily apparent in FIGURES 1 and 2 back member 14 is pivotable with respect to face member 13 to open outwardly at the top thereof whereby clamp 10 can be easily mounted on bedframe 11 with face member 13 disposed on the outside of bedframe 11 and back member 14 disposed on the inside of bedframe 11, and with arms 15 extending beneath bedframe 11 and flanges 18 engaging top portion 19 of bedframe 11.

Face member 13 additionally carries projecting portions 20 and 21 having axially corresponding openings 22 and 23 therein respectively. Opening 23 is elongated, similar to the opening 23' shown in FIGURE 5, for reasons that will become clear as the description continues. A sleeve 25, as best shown in FIGURE 2, is slidably disposed in opening 23 and is retained therein by its annular flange 26 and a threaded nut 27. A locking member 24 is disposed on sleeve 25 through the opening 28 of locking member 24 and is retained thereon by the nut 27. Spacer 29 spaces locking member 24 from lower projecting portion 21. Locking member 24 has cam surfaces 30 and a handle portion 31.

Having placed clamp 10 on bedframe 11 as earlier described with pole 12 inserted through opening 22 and sleeve 25, handle 31 may be swung to either side, as shown in FIGURE 1, to lock clamp 10 and pole 12 to bedframe 11. It will be understood that as handle 31 is thrown to one side or the other, the corresponding cam 30 will bear against the lower portion 14a of back member 14 which extends below hinge pin 17 and thus causes back member 14 to pivot its upper portion 14b into engagement with the inside of bedframe 11. Simultaneously, sleeve 25 is forced outwardly from back member 14 in elongated opening 23 by cam 30 bearing on back member 14. This

causes pole 12 to bind in opening 22 and in sleeve 25 and thus become locked in clamp 10 which in turn is locked to bedframe 11. It can be readily understood that the position of the clamp and the height of the pole can be easily and quickly adjusted merely by swinging locking member 24 outwardly to loosen both pole and clamp and repositioning same by sliding the clamp along the bedframe and/or the pole up or down in the clamp openings and then relocking both simply by swinging handle 31 inwardly again.

In another preferred embodiment of my invention, illustrated in FIGURES 3 to 5, I provide a face member 13' having an upper portion 40 and a lower portion 41 that are hingedly joined as at reference 42 by hinge pin 43. Corresponding portions of the embodiment about to be described carry the same reference numbers as applied in the first described embodiment with a prime (') sign added thereto. Mounted on hinge pin 43 is a single loop torsion spring 44 having one end bearing against upper portion 40 and the other against lower portion 41 which biases upper and lower portions 40 and 41 to a coplanar attitude. It can be readily understood that the above-described spring-hinge structure greatly facilitates the mounting of my clamp on bedframe 11' by simply squeezing projecting portions 20' and 21' toward each other to 25 provide a larger opening between face member 13' and back member 14' into which bedframe 11' may readily be disposed.

As in the first described embodiment, projecting portions 20' and 21' have axially corresponding openings 22' and 23', the latter of which is elongated and has slidably disposed therein the sleeve 25'. Locking member 24' is disposed on sleeve 25' through the opening 28' thereof and is retained thereon by the nut 27', as best shown in FIGURE 4. Preferably, I further provide a rubber collar 45 and washer 46 disposed on sleeve 25' between annular flange 26' and projecting portion 21'.

Upper member 40 has flanges 18' which engage top portion 19' of bedframe 11' and lower member 41 has projecting arms 15' which support back member 14' by virtue of hinge pin 17' in hinge eyes 16'. Back member 14' has a lower portion 14a' disposed below hinge pin 17' and an upper portion 14b' disposed above hinge pin 17'. Preferably, portion 14a' is bent slightly back from face member 13' for reasons that will become clear as the description continues.

When clamp 10' is mounted on bedframe 11' with pole 12' inserted through opening 22' and sleeve 25', locking member 24' may be swung in either direction to engage either of cam surfaces 30' with portion 14a' of back member 14'.

As earlier described, when cam surface 30' engages lower portion 14a', upper portion 14b' of back member 14' is pivoted at pin 17' to engage the back of bedframe 11'. Simultaneously, sleeve 25' in opening 23' is moved outwardly or away from back member 14', which action shifts pole 12' and binds pole 12' in opening 22' and sleeve 25'. Due to the yieldability of rubber collar 45, locking member 24' can shift downwardly and correspondingly cam surface 30' shift downwardly along the slightly receding portion 14a' of back member 14'. This yieldability of locking member 24' in a vertical as well as horizontal direction permits the operator to swing handle 31' all the way in toward bedframe 11' and out of the way regardless of variations of thickness in bedframe 11' and thus makes my clamp more universal in this respect. Here too, the clamp and pole may easily be adjusted simply by unlocking and moving the pole up or down in the clamp and the clamp along the bedframe as desired without removing them from the bedframe and then locking them again with one easy motion when positioned as desired.

While I have shown and described certain present preferred embodiments of my invention, it is to be distinctly understood that the invention is not limited thereto but

may be otherwise variously embodied within the scope of the following claims.

I claim:

1. A clamp for use with hospital beds and the like in combination with a pole member comprising a face member adapted to engage an outer portion of a bedframe, a back member adapted to engage an inner portion of a bedframe, said face member having arm means adapted to extend below and across the lower portion of a bedframe, said back member being pivotally supported on said arm means whereby a portion of said bedframe is disposed between said face and back members, said face member having flange means adapted to engage a top portion of said bedframe, said face member having projecting portions disposed in spaced relation one above the other with axially corresponding openings therein, said pole member extending through said openings, said back member having a lower portion extending below said pivotal support and a locking member mounted on said face member swingable to simultaneously engage said lower portion of the back member and said pole member whereby said back member is pivoted into engagement with said inner portion of a bedframe and said pole member is bound in said openings.

2. A clamp for use with hospital beds and the like in combination with a pole member comprising a face member adapted to engage an outer portion of a bedframe, a back member adapted to engage an inner portion of a bedframe, said face member having arm means adapted to extend below and across the lower portion of a bedframe, said back member being pivotally supported on said arm means whereby a portion of said bedframe is disposed between said face and back members, said face member having flange means adapted to engage a top portion of said bedframe, said face member having projecting portions disposed in spaced relation one above the other with axially corresponding openings therein, said pole member extending through said openings, said back member having a lower portion extending below said pivotal support and a locking member yieldably mounted on the lower of said projecting portions and swingable therewith and having an opening therethrough corresponding with said flange openings through which said pole member also extends, said locking member being swingable to simultaneously engage said lower portion of the back member and said pole member whereby said back member is pivoted into engagement with said inner portion of a bedframe and said pole member is bound in said openings.

3. A clamp for use with hospital beds and the like in combination with a pole member comprising a face member adapted to engage an outer portion of a bedframe, a back member adapted to engage an inner portion of a bedframe, said face member comprising upper and lower elements hingedly joined and swingable with respect to each other, said lower element having arm means adapted to extend around the lower portion of a bedframe, said back member being pivotally supported on said arm means whereby a portion of said bedframe is disposed between said face and back members, said upper element having flange means adapted to engage a top portion of said bedframe, said upper and lower elements having projecting portions disposed in spaced relation one above the other with axially corresponding openings therein, said pole member extending through said openings, said back member having a lower portion extending below said pivotal support and a locking member mounted on said face member swingable to simultaneously engage said lower portion of the back member and said pole member whereby said back member is pivoted into engagement with said inner portion of a bedframe and said pole member is bound in said openings.

4. A clamp for use with hospital beds and the like in combination with a pole member comprising a face member adapted to engage an outer portion of a bedframe, a

back member adapted to engage an inner portion of a bedframe, said face member comprising upper and lower elements hingedly joined and swingable with respect to each other, spring means resiliently urging the respective elements of said face member into coplanar relationship, said lower element having arm means adapted to extend below and across the lower portion of a bedframe, said back member being pivotally supported on said arm means whereby a portion of said bedframe is disposed between said face and back members, said upper element having flange means adapted to engage a top portion of said bedframe, said upper and lower elements having projecting portions disposed in spaced relation one above the other with axially corresponding openings therein, said pole member extending through said openings, said back member having a lower portion extending below said pivotal support and a locking member mounted on said face member swingable to simultaneously engage said lower portion of the back member and said pole member whereby said back member is pivoted into engagement with said inner portion of a bedframe and said pole member is bound in said openings.

5. A clamp for use with hospital beds and the like in combination with a pole member comprising a face member adapted to engage an outer portion of a bedframe, a back member adapted to engage an inner portion of a bedframe, said face member comprising upper and lower elements hingedly joined and swingable with respect to each other, said lower element having arm means adapted to extend below and across the lower portion of a bedframe, said back member being pivotally supported on said arm means whereby a portion of said bedframe is disposed between said face and back members, said upper element having flange means adapted to engage a top portion of said bedframe, said upper and lower elements having projecting portions disposed in spaced relation one above the other with axially corresponding openings therein, said pole member extending through said openings, said back member having a lower portion extending below said pivotal support and a locking member yieldably mounted on the lower of said projecting portions and swingable therewith and having an opening therethrough axially corresponding with the openings of said projecting portions through which said pole member also extends, said locking member being swingable to simultaneously engage said lower portion of the back member and said pole member whereby said back member is pivoted into engagement with said inner portion of a bedframe and said pole member is bound in said openings.

6. A clamp for use with hospital beds and the like in combination with a pole member comprising a face member adapted to engage an outer portion of a bedframe, a back member adapted to engage an inner portion of a bedframe, said face member comprising upper and lower elements hingedly joined and swingable with respect to each other, spring means resiliently urging the respective elements of said face member into coplanar relationship, said lower element having arm means adapted to extend below and across the lower portion of a bedframe, said back member being pivotally supported on said arm

means whereby a portion of said bedframe is disposed between said face and back members, said upper element having flange means adapted to engage a top portion of said bedframe, said upper and lower elements having projecting portions disposed in spaced relation one above the other with axially corresponding openings therein, said pole member extending through said openings, said back member having a lower portion extending below said pivotal support and a locking member yieldably mounted on the lower of said projecting portions and swingable therewith and having an opening therethrough axially corresponding with the openings of said projecting portions through which said pole member also extends, said locking member being swingable to simultaneously engage said lower portion of the back member and said pole member whereby said back member is pivoted into engagement with said inner portion of a bedframe and said pole member is bound in said openings.

7. A clamp for use with hospital beds and the like in combination with a pole member comprising a face member adapted to engage an outer portion of a bedframe, a back member adapted to engage an inner portion of a bedframe, said face member comprising upper and lower elements hingedly joined and swingable with respect to each other, spring means resiliently urging the respective elements of said face member into coplanar relationship, said lower element having arm means adapted to extend below and across the lower portion of a bedframe, said back member being pivotally supported on said arm means whereby a portion of said bedframe is disposed between said face and back members, said upper element having flange means adapted to engage a top portion of said bedframe, said back member having a lower portion extending below said pivotal support, said upper and lower elements having projecting portions disposed in spaced relation one above the other with axially corresponding pole receiving openings therein, the opening in the lower of said projecting portions being elongated outwardly from said face and back members and locking means slidably disposed in said elongated opening and swingable therein and yieldable vertically with respect to said lower projecting portion and having a pole receiving opening therethrough axially corresponding with the openings of said projecting portions, said pole member extending through said openings, said locking member being swingable to simultaneously engage said lower portion of the back member and said pole member whereby said back member is pivoted into engagement with said inner portion of a bedframe and said pole member is bound in said openings.
